United States Patent Office

Des. 204,707
Patented May 10, 1966

204,707

BOTTLE

Horace P. Abbott, Old Greenwich, Conn., assignor to
Lever Brothers Company, New York, N.Y., a corpora-
tion of Maine

Filed June 1, 1965, Ser. No. 85,527

Term of patent 14 years

(Cl. D58—6)

FIG.2.

FIG.1.

FIG. 6.

FIG. 5.

FIG. 3.

FIG. 4.

FIGURE 1 is a front elevational view of a bottle showing my new design, with the closure for the bottle closed;

FIGURE 2 is a front elevational view of the opposite side thereof with the closure open;

FIGURE 3 is a plan view thereof with the closure closed;

FIGURE 4 is a bottom plan view thereof;

FIGURE 5 is a side elevational view thereof with the closure closed; and

FIGURE 6 is a side elevational view of the opposite side thereof with the closure closed.

I claim:

The ornamental design for a bottle, as shown.
